UNITED STATES PATENT OFFICE.

HENRY DRYSDALE, OF LONDON, ENGLAND, ASSIGNOR TO INTERNATIONAL CARTONS LIMITED, OF LEYTON, ESSEX, ENGLAND, A COMPANY OF GREAT BRITAIN.

FOLDING BOX OR RECEPTACLE.

Application filed April 4, 1922. Serial No. 549,638.

To all whom it may concern:

Be it known that I, HENRY DRYSDALE, a British subject, residing at 136 Philip Lane, Tottenham, London, England, have invented 5 certain new and useful Improvements in Folding Boxes or Receptacles, of which the following is a specification.

This invention relates to improvements in folding boxes or receptacles, commonly 10 known in the trade as cartons and referred to hereinafter as such. It has for its object to provide a collapsible carton permanently lined with paper or the like so that when closed the carton is powder-tight 15 and substantially air-tight at the ends.

It has already been proposed to line such 20 cartons with a non-absorbent material, such as wax paper, or paraffin paper removably adherent thereto, that is, the paper can be readily stripped off when desired without 25 rupture to either itself or the blank and also to attach said lining to divided end flaps of the carton, so that when two of the opposite flaps were turned in the lining was stripped off from parts of the two other 30 flaps to form folds along diagonal lines on these flaps. Obviously careful manipulation was necessary in the closing of such 35 cartons to cause the removably attached lining to be detached precisely along the required lines, and much wastage was liable to occur if the requisite skill and care were not fully exercised.

Now, according to the present invention, 40 the lining is permanently attached to the carton and also to the end flaps, so, however, that it is glued to two of these end flaps over the whole of their surfaces, while to the two other end flaps it is glued along triangular surfaces having their bases in the base or bottom edge of these flaps. This provision enables the carton blanks so lined to be safely manipulated and the closing of 45 the carton and automatic folding in of the lining material to be effected rapidly and in a most reliable manner without wastage.

Cartons of this character may, moreover, 50 be printed in a single machine at the same time that they are prepared for folding and the printing may be in several colors without danger of the lining becoming detached.

In order that my invention may be clearly understood I will now describe one em-

bodiment of the same with reference to the accompanying drawings, in which— 55

Fig. 1 shows a carton blank, creased, cut at its ends and covered with an adhesive over predetermined portions in order to fix a lining sheet of material thereon to extend over the whole carton blank; and 60

Fig. 2 is a pictorial view of a box or carton, formed from a blank as shown in Fig. 1 indicating clearly how the folding of the small flaps or cut end members of the carton automatically assures the closing also of the 65 lining material.

The shaded parts in Fig. 1, indicate the areas of the carton blank covered by the adhesive. As shown on two of the end pieces of flaps 1 of the carton blank at each end, the 70 gummed area is shown to be of triangular nature, the outside edges of the triangle being limited by lines 2 drawn from the base corners of the flaps. These lines 2 are particularly disposed in relation to each other, 75 that is, at right angles, so as to form the most desirable folding line, as clearly indicated in Fig. 2 by the same reference numeral.

It is immaterial whether the area within 80 the triangle is covered with adhesive or not, for it is essential only to fix a strip of the lining material along the lines 2, so that when the small flaps 3 are first turned in, as clearly shown in Fig. 2, the lining material on the flaps 1 is folded first upon itself as shown at 7 in Fig. 2, on each side of the carton, and then interfolded with the flaps when the flaps 1 are subsequently turned in to complete the closure thereby effecting a 85 powder-tight and substantially airtight closure to the end of the carton.

The area covered by adhesive on the small flaps 3 or its actual configuration, may be 90 varied so long as the adhesive holds the lining to the flaps in order to ensure the required operation, when folding.

The area 4 of adhesive shown at the extremities of the side walls of the carton body, holds the lining in place in the carton during the folding operation, and it will be clear that supposing, for economical reasons, the lining does not extend through the length of the carton but is cut off along lines, as indicated by the dot and pick lines 5, an 100 105 equally effective result will be obtained.

The side strip 6 of the carton body, is, as shown, gummed also on the outside for fixing to the adjacent side of which the outside small flap 3 is a part.

5 What I claim and desire to protect by Letters Patent is:—

A carton comprising a rectangular box shaped body portion and marginal flaps thereon divided longitudinally into separate 10 flaps at one or both ends and an inner uncut lining cuff permanently attached to the body portion and two opposite flaps along the whole surface thereof, and to the two other flaps along triangular surfaces hav-

ing their base in the base of these flaps 10 whereby by turning in the pair of opposite flaps having the lining portions wholly attached thereto the unattached parts of the lining on the two other flaps are folded inwardly substantially as and for the purpose set forth.

In testimony whereof I affix my signature in presence of two witnesses.

HENRY DRYSDALE.
